[57] CLAIM

The ornamental design for a golf club head, as shown and described.

DESCRIPTION

FIG. 1 is a top plan view of the golf club head showing my new design.

FIG. 2 is a front elevation view of the golf club head of
FIG. 1.

FIG. 3 is a side view of the golf club head as viewed from the right side of FIG. 1.

FIG. 4 is a back elevation view of the golf club head of
FIG. 1.

FIG. 5 is the bottom view of the golf club head of FIG.
1.

FIG. 6 is an isometric view of the golf club head of
FIG. 1.

The side view of the club as viewed from the left of
FIG. 1 is the same as FIG. 3.
